Inventor:
Lambert Diesel,
By Eugene Cawam
Atty.

UNITED STATES PATENT OFFICE.

LAMBERT DIESEL, OF CHICAGO, ILLINOIS.

ANTIGLARE DEVICE FOR HEADLIGHTS.

Application filed September 12, 1925. Serial No. 55,900.

To all whom it may concern:

Be it known that LAMBERT DIESEL, a citizen of the United States, residing at Chicago, in the county of Cook and State of Illinois, has invented certain new and useful Improvements in Antiglare Devices for Headlights, of which the following is a specification.

This invention relates to anti-glare devices for automobile and other headlights.

The object of my invention is to provide an anti-glare device which may be readily applied to a headlight glass or lens for diffusing the light and eliminating the glare without appreciably lessening or diminishing the amount of light emitted from the lamp.

Specifically, a device of my invention includes two discs to be placed over the light-emitting opening of the lamp and made of translucent paper or other translucent material, with one disc continuous and unbroken and the other disc having a plurality of apertures or holes distributed over the same and covered by the non-perforated other disc.

In the accompanying drawings—

Fig. 1 is a front view of a headlight equipped with an anti-glare device of my invention;

Fig. 2 is an enlarged vertical sectional view on line 2—2 of Fig. 1; and

Fig. 3 is a fragmentary view to illustrate details of structure to be hereinafter described.

In Fig. 2 of the drawings, I have shown just enough of the headlight structure to illustrate the application of my invention thereto. In said figure, 1 indicates the outer casing or shell of the lamp, 2 the reflector therein, and 3 the ring for clamping the headlight glass or lens 4 in place over the light-emitting opening of the lamp.

The device of my invention comprises two relatively thin translucent discs 5, 6. These discs may be made of paper or other translucent material which is not transparent and which will transmit light without appreciably dimming the same.

One of the discs, for instance the one 6, is provided with a plurality of relatively small holes or apertures 7 distributed over the discs and covered on one side by the non-perforated other disc 5 when the two discs are placed together and extend over the

light-emitting opening of the lamp, as shown in Fig. 2. By this arrangement there is only one layer of disc material covering the holes 7 and two layers of disc material elsewhere. This allows more light to pass through the 60 discs at the holes than elsewhere, and as the holes are relatively small and are regularly distributed over the entire area of the disc 6, the glare of the lamp will be eliminated without appreciably dimming or diminishing the amount of light emitted therefrom. This is an important advantage for automobiles, in that it allows night driving with the bright lights turned on to light up the roadway without the blinding glare as heretofore.

The discs 5, 6 are usually placed inside of the glass or lens 4 to protect them from injury and from the weather, and are clamped in place between the lens 4 and 75 outer edge of the lamp opening by the ring 3, as shown in Fig. 2.

The discs provide a simple and inexpensive anti-glare device and one that may be easily and readily applied and installed 80 either to lamps when first placed on the car or afterwards. Instead of being made from paper or other like material, the discs may be made of glass for use in place of the lens 4. In such case, the outside disc 5 85 takes the place of the lens 4.

I claim as my invention:

1. An anti-glare device for headlights, comprising two relatively thin flat discs of translucent material, said discs being placed 90 one against the other and being substantially equal in size so as to be coextensive, one of said discs being imperforate, and the other disc having a plurality of holes distributed over the same and covered by the other disc. 95

2. An anti-glare device for headlights, comprising two relatively thin flat discs of translucent paper material, said discs being placed one against the other and being substantially equal in size so as to be coextensive, one of said discs having a plurality of relatively small holes of substantially the same size distributed regularly over the same and covered by the other disc so that there is a single layer of disc material at the 100 holes and a double layer of said material elsewhere. 105

In testimony whereof he affixes his signature this 17th day of April, 1925.

LAMBERT DIESEL.
